(57) **CLAIM**

The ornamental design for a graphical user interface for displaying content selections on a display panel, as shown and described.

DESCRIPTION

FIG. 1 is a front view of a graphical user interface for displaying content selections on a display panel;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of a eighth embodiment thereof;

FIG. 9 is a front view of a ninth embodiment thereof;

FIG. 10 is a front view of a tenth embodiment thereof;

FIG. 11 is a front view of a eleventh embodiment thereof; and,

FIG. 12 is a front view of a twelfth embodiment thereof.

The broken line drawings of the display panel forms no part of the claimed design. The text and images shown in dotted lines are for illustrative purposes only and form no part of the claimed design.
